The ornamental design for the waterproof electrical connector, as shown and described.

DESCRIPTION

FIG. 1 is a front perspective view of a waterproof electrical connector,

FIG. 2 is a rear perspective view thereof,

FIG. 3 is a front view thereof,

FIG. 4 is a rear view thereof,

FIG. 5 is a left side view thereof,

FIG. 6 is a right side view thereof,

FIG. 7 is a top plan view thereof,

FIG. 8 is a bottom plan view thereof; and,

FIG. 9 is a sectional view cut by 9-9 line in FIG. 3 thereof.

The broken lines in the FIGS. depict environmental subject matter and form no part of the claimed design.
